UNITED STATES PATENT OFFICE.

BYRON A. BROOKS, OF BROOKLYN, NEW YORK.

TYPE-WRITING MACHINE.

SPECIFICATION forming part of Letters Patent No. 423,900, dated March 25, 1890.

Application filed May 19, 1884. Serial No. 131,967. (No model.)

To all whom it may concern:

Be it known that I, BYRON A. BROOKS, a citizen of the United States, residing in Brooklyn, in the county of Kings and State of New York, have invented certain new and useful Improvements in Type-Writing Machines, of which the following is a description in such full, clear, concise, and exact terms as to enable any one skilled in the art to which my invention belongs to make and use the same, reference being had to the accompanying drawings, making part of this specification, and to the letters and figures of reference marked thereon.

15 My invention consists of certain novel parts and combinations of parts constituting an improved type-writer. The points of novelty will be designated in the claims concluding this specification.

20 Similar letters and figures of reference indicate corresponding parts in all the figures.

Figure 1 is a side view of my improved machine. Fig. 2 is a top view, and Fig. 3 a front view, of the same. Figs. 4 and 5 are respectively side and front views, partly in section, of my improved type-bars.

Referring to Fig. 1, C' is one of a series of bell-crank levers carrying the types a b c and pivoted to oscillating or vibrating bell-30 crank levers A, set in the arc of a circle, and which in turn are pivoted on frame h' and are provided with the projections g.

A' are a series of key-levers set in the frame B' and fulcrumed at q', the rear ends of each 35 of which levers are connected by springs d and rods e, respectively, to lever-arms E and D of the aforesaid bell-crank levers.

y is a stop-piece formed into steps 1, 2, and 40 3, having a vertical movement imparted to it by the levers B. The stop y being in the position illustrated in the drawings, Fig. 1, when the key A' is depressed the projection g on the lever A E by means of spring d is pressed against the step 1, and the type-bar C' D by 45 means of rod e is thrown down to print the letter "a." When the stop y is raised into the second position, the projection g is thrown forward against the stop 2 and the letter "b" is printed, and when the stop is raised to the 50 third position the projection is thrown forward against the stop 3 and the letter "c" is printed.

My present form of type-writer may be arranged to print directly from the type without the use of an inking-ribbon, and in the 55 drawings I have illustrated one means of automatically inking the type for this purpose.

C is a pad or roller, which may be supplied with ink by intermediate rollers or in any well-known manner. It is connected by the 60 bent rod C' with a rotary cam H, against which the end of the rod G bears, which rod is pivoted to the frame B' at s' and is actuated by a lever-arm connected to the spacing-key D' of the machine. Each time, therefore, the key D' is depressed the inking roller or pad passes over or is pressed against the 65 face of all the types, and returns to the position illustrated in the drawings by the action of a spring H', connected to the cam H. 70 The projection C''' from the rod C' immediately beneath the ink-roll indicates the position of a distributing-roller bearing against said ink-roll for the purpose of supplying and distributing ink evenly thereon.

75 The bars i i, Figs. 1 and 3, are tracks upon which the platen-carriage slides. This carriage holds the pivoted cylindrical platen E and the device for revolving the same upon its axis. The platen-carriage is free to move 80 longitudinally upon the bars i i, said longitudinal movement being imparted by the rack k k, connected thereto, in combination with the revolving screw j, mounted upon the shaft o, which is in turn actuated by means 85 of a ratchet-wheel h and pawl q, (see Fig. 1,) carried by the pivoted lever s, connected by arm u to bar I, pivoted at one end to the frame of the machine and actuated by the vertical movement of the bar t, attached thereto. The bar t is provided with a series of set-screws r r, one for each key-lever A', as shown in Fig. 3. These key-bars A' each have a given vertical movement, and it will be readily seen that the distance the bar t rises 90 95 when a given lever A' is actuated, and therefore the lateral motion imparted to the platen E, may be governed by the adjustment of these set-screws. This device is for the purpose of regulating the spaces between the impressions of the type and to impart the amount of lateral motion to the platen necessary to insure an equal space between each two letters, whether the letter be broad or

narrow. The descent of the bar *t* is quickened by the springs *l' l'*. A spring pulley-drum *l*, tending to draw the platen-carriage toward the left hand to facilitate the horizontal movement of the platen in spacing, may be employed, said tendency, however, being resisted by the screw *j* while it remains at rest. The revolution of the screw *j* may be reversed to draw the platen-carriage toward the right hand by means of a string *n*, attached to the shaft *o*. This string may be combined with a pawl, ratchet-wheel, and spring to immediately draw it toward the cylinder when released. The pawl *q* is raised to allow the ratchet-wheel *h* to be turned back by means of a pin projecting from the pivoted arm *J*, through one end of which the string *n* passes in an inclined friction-slot *m'*, thereby raising the said pawl when the string *n* is drawn outward. Other devices well known in the arts operating to raise the pawl to allow the worm-wheel to revolve in the opposite direction may be employed without altering the principle or function of the combination.

25 The platen *E* is provided with a ratchet-wheel *x* and a lever *y'*, pivoted on the platen-shaft carrying the pawl *z*, which engages with the said ratchet-wheel. This lever is provided with a spring, which tends to turn it with a right-hand revolution upon its axis. The lower arm of the lever *y'* rests on a horizontal bar *x'*, tapered at one end, (see Fig. 1,) which gives to the lever *y'* a reciprocating or vibrating motion each time the platen is moved horizontally to and from the extreme left position, thereby automatically (by means of the said ratchet-wheel and pawl) revolving the platen on its axis through a given arc to space between lines of print when the 30 platen moves from its extreme left position toward the right.

35 The form of type-bar I prefer to use in my machine is illustrated in detail in Figs. 4 and 5. It consists of a thin piece of metal set on a short pivot, about which it revolves. About the pivot-point I provide the bar with bearing-surfaces parallel with the plane of vibration of the type-bar to prevent lateral vibration. Both parts of my compound type-bar 40 should be made of such thin pieces of metal, and both pivots, as illustrated at *F*, Fig. 5; but in such figure I have illustrated only the upper or type-bearing section of the bar.

45 One of the objects attained in the machine which is the subject-matter of these Letters Patent is that the printing as it progresses is constantly in sight of the operator. To accomplish this, the type-bars must be set to strike on top of the platen and cannot be distributed throughout the entire circumference of a circle. The type-bars must therefore be made thin to economize space. For the same purpose the standards to which the bars are pivoted must also be thin.

55 50 55 60 65 The paper which receives the impression of the type enters above the guide *v*, passes between the platen and guide-wheel *F*, then

between the platen and guide-wheel *F'*, and then out between the guides *v* and *w*. Upon the back end of the bars *s* is attached a spring *o'*, which rests upon the periphery of the wheel *h* when the bar *s* is in the position shown. When the said bar is turned with a right-hand revolution about its axis, the spring *o'* is raised out of connection with wheel *h*. 70 This spring acts as a brake upon the revolution of the wheel *h* to prevent the momentum of said wheel carrying it too far when operated by the throw of the pawl *q*, and, being raised out of connection with the wheel *h* 80 when the pawl *q* is slipping over the ratchet-teeth on said wheel, avoids waste of force.

I do not herein claim, in a type-writing machine, the combination of a type-bar, a vibrating support to which it is pivoted, and a key-lever carrying a rod attached to said key-lever and to said type-bar, as such subject-matter is covered by a pending application filed March 23, 1886, Serial No. 196,215.

Having thus described my invention, I claim and desire to secure by Letters Patent—

1. In a type-writing machine, the combination of the adjustable stop-piece and a type-bar consisting of two bell-crank levers, one being pivoted to a stationary support and provided with a stop projection, and the other being pivoted to the last-mentioned lever and carrying the types, and both being connected to and operated by a key-lever, substantially as described.

100 2. In a type-writing machine, the combination, with the platen-carriage, of a rack and worm-wheel engaging therewith to move said carriage longitudinally in both directions by the right-hand and left-hand revolution of said worm-wheel, and a ratchet-wheel, pawl, and pulley attached to the worm-wheel shaft to control the motion of said worm-wheel, said pawl being raised out of contact with its ratchet-wheel automatically by means substantially as described when the revolution of the ratchet-wheel is reversed to draw the platen back.

105 3. In a type-writing machine, and in combination with the platen-carriage, a spring-drum, rack, screw, pawl and ratchet to revolve said screw, and a spacing-bar connected to the pawl, substantially as described.

110 4. In a type-writing machine, the combination, with the platen *E*, friction-rollers *F* and *F'*, and guides *v* and *w*, between which guides the paper to be printed on enters, and on top of which the paper, after it has received the impression of the type, returns, substantially as described.

115 5. In a type-writing machine, in combination with a type-bar bearing two or more types, a rod *e*, a bell-crank lever *A E*, provided with stop *g*, stop-piece *y*, spring *d*, and key-lever *A'*, by means of which the movement of the type-bar is governed to print its several types, substantially as described.

120 6. In a type-writing machine, the combination of a bell-crank lever *A E*, to which the

bar carrying the types is pivoted, rod *e*, stop *y*, spring *d*, key-lever *A'*, and longitudinally-traveling platen *E*, with type-bars set in the arc of a circle, each carrying two or more types set in the line of the radius of said circle and arranged to reciprocate therein, substantially as described.

7. In a type-writing machine, a carriage-support consisting of tracks on which the carriage runs, combined with standards attached to the frame of said machine and curved so as to provide a support both above and below

said platen and be entirely out of the path of said carriage, so that the end of said carriage may travel beyond the curved standards, substantially as described.

8. In a type-writing machine, an inking-pad, combined with and operated by the key-lever by which spacing between words is accomplished, substantially as described.
